UNITED STATES PATENT OFFICE.

FRED LANGBEIN, OF NEWARK, NEW JERSEY.

FLY-TRAP GARBAGE-COVER.

1,290,760.

Specification of Letters Patent.

Patented Jan. 7, 1919.

Application filed June 4, 1918. Serial No. 238,174.

To all whom it may concern:

Be it known that I, FRED LANGBEIN, a citizen of the United States, residing at Newark, in the county of Essex and State of New Jersey, have invented certain new and useful Improvements in Fly-Trap Garbage-Covers, of which the following is a specification.

This invention relates to metallic shipping and storing vessels, and more especially to garbage receptacles; and the object of the same is to produce an improved cover or closure for a garbage can which is so constructed as to trap flies and other insects on both the interior and exterior of the can.

A second object is to make the cover in such a way that it constitutes a fly trap even when it is removed from the can.

A third object is to provide special means for cleaning the trap of the flies caught by it.

Other objects will appear in the following specification. Referring to the accompanying drawings—

Figure 1 is a central vertical section through the upper portion of a garbage can with this improved cover,

Fig. 2 is a plan view broken away in segments to show the different parts in plan or section,

Fig. 3 is an enlarged sectional detail, Fig. 4 is a perspective detail of the spring.

Referring to the drawings, I provide an ordinary cylindrical garbage can G, with a cover C having a handle H. All these parts are by preference of galvanized iron or other metal which will not rust or become contaminated by the contents. No novelty whatever is claimed for the can, and around the mouth of the same is herein illustrated an ordinary bead B.

Coming now to the present invention I form the upper portion of the cover C in dome-shape as indicated at 1, and its top 2 is practically flat excepting that beneath the handle it is arched a little at 3 and the arched portion is perforated at 4. I may here remark that the word "perforations" as used herein is designed to indicate holes or openings too small for the passage of flies and other insects which are to be trapped by this device. The side wall 5 of the dome 1 is carried outwardly and crimped at 6 over an outturned flange at the upper edge of a skirt 7 which, as shown herein, is a rather wide annular band of a size to inclose the

bead B and preferably having itself an outturned bead 8 at its lower edge. Attention is invited to the fact that the side wall 5 of the cover is not carried straight down into this skirt, and the use of the crimp is for other purposes than merely connecting the two members 5 and 7. When the cover is upon the can C the skirt 7 passes outside the same as seen in Fig. 1; when the cover is removed from the can and placed upon some support, as the floor or ground, the bead 8 at the lower end of the skirt rests thereon and the cover itself constitutes a trap as will be described below.

Disposed within and extending horizontally across the cover are two partitions 10 and 11 spaced one above the other as seen in Fig. 1 to produce an interposed passage 12. The partition 10 is a flat disk whose edge is caught within the crimp 6. The partition 11 is likewise a flat disk excepting that it has an upturned and thence outturned flange at its edge also caught within said crimp, and where it is upturned it is pierced with holes indicated at 19 which register with holes indicated at 9 in the skirt 7 just beneath the crimp; and through this partition 11 inside its upturned flange are other holes 18. The upper partition is perforated as indicated at 13 in Fig. 3, whereas most of the lower partition is solid or imperforate. With the exception of the upturned and outturned flange around the periphery of the lower partition, both these partitions are substantially flat; but they are provided through their centers with large openings, best indicated at 15 in Fig. 1, and therefore they are in effect annular partitions.

Disposed within said central openings is what might be called the trap proper. It has an upright cylindrical wall 20 provided with openings 21 for admitting the flies, a flat bottom 22 also provided with openings 23 and a bead 24 around its edge larger than the central holes 15 through the partitions 10 and 11, and a dome-like cover or top 25 of wire mesh opening at its apex through a neck 26 directed upward toward the center of the top of the cover as seen in Fig. 1. A spring as best seen in Fig. 4 has one end 27 fastened in the lower partition, a coil 28 rising through the same and engaged over a pin 29, and a long arm 30 underlying the bottom 23 of the trap and of the shape best seen in Fig. 4 so that it extends for a con-

siderable distance beneath said bottom, its extremity having a handle 31 as shown. Normally the long arm of this spring bears upward against the bottom of the trap, and 5 holds the whole trap upward so that its beaded edge 24 rests beneath the lower partition 11 around the central opening 15 in the same.

With the parts assembled as seen in Fig. 10 1, flies within the garbage can C may pass upward through the holes 18 and 23. Through the former they get into the passage 12, which leads through the openings 21 into the trap. Through the holes 23 they 15 pass directly into the trap. Therein they are attracted by the light overhead which shines through the perforations 4 in the cover and through the wire mesh 25, and they fly upward, crawling eventually 20 through the neck 26 and becoming trapped in the space under the cover and above the upper partition 10. Meanwhile also flies and other insects on the outside of the garbage can may pass through the registering 25 holes 9 and 19 into the passage 12, and follow the same course into the space above the trap proper and under the cover. Therefore with the parts assembled this device catches flies and insects on both the inside 30 and the outside of the garbage can. When the cover is taken off and seated on the ground, it will yet catch insects which pass in through the openings or holes 9 and through the passage 12 as described above. 35 From time to time the spring is moved downward by pulling on the handle 31, (the cover at this time being off the can) and the trap proper removed from the large holes and cleaned. This can be done by 40 shaking the flies and carcasses out of it, or running scalding water through it. With the trap out of the large openings 15, the carcasses within the cover can now be shaken out, or burned or scalded in the same manner. Thereafter the parts are reassembled, 45 and the cover put back onto the garbage can.

The foregoing description and the drawings have reference to what may be considered the preferred, or approved form of 50 my invention. It is to be understood that I may make such changes in construction and arrangement and combination of parts, materials, dimensions, et cetera, as may prove expedient and fall within the scope 55 of the appended claims.

Having thus fully described my invention, what I claim as new and desire to secure by Letters Patent, is:—

1. The combination with a cylindrical receptacle having a bead around its upper edge; of a cover having a skirt adapted to inclose said bead, spaced partitions across the interior of the cover, the skirt having holes opening to the passage between said 60 partitions, and means at the center of said 65 partitions, and means at the center of said

passage for directing the trapped insects upward into the space beneath the top of the cover.

2. The combination with a cylindrical receptacle having a bead around its upper edge; of a cover having a skirt adapted to inclose said bead, two partitions across the interior of the cover, the skirt having holes opening to the passage between said partitions, and both partitions having large central openings, a cylindrical wall fitting within said openings and provided with holes for admitting insects from the passage, and a dome-like top to said cylindrical element having an open neck communicating with the interior of the cover. 70 75 80

3. The herein described cover for garbage cans and the like, the same having a dome-like top, a crimp around its side wall, a skirt having an outturned flange at its upper edge caught in said crimp and holes beneath said flange, an upper partition with its edge caught in said crimp, a lower partition with its edge turned upwardly and outwardly and caught in said crimp and the upturned portion provided with holes registering with those in the skirt, and means at the center of said partitions for directing the insects from between them to the space above the upper partition and beneath the top of the 90 95 cover. 95

4. The herein described cover for garbage cans and the like, the same having a dome-like top, a crimp around its side wall, a skirt having an outturned flange at its upper edge caught in said crimp and holes beneath said flange, an upper partition with its edge caught in said crimp, a lower partition with its edge turned upwardly and outwardly and caught in said crimp and the upturned portion provided with holes registering with those in the skirt, the upper partition having fine perforations and the lower partition having large holes around it near its edge and both partitions having large openings at their centers, a cylindrical element mounted in said opening and provided with holes communicating with the passage between said partitions, a conical dome on the top of said element, and a reduced open neck at the apex of said dome. 100 105 110 115

5. In a device of the type described, the combination with a dome-like cover having openings through its skirt, and partitions across the interior of the cover respectively above and below said openings; of a trapping element disposed at and mounted through the centers of said partitions and having inlet openings communicating with the passage between them and an outlet communicating with the space above said upper partition. 120 125

6. In a device of the type described, the combination with a dome-like cover having openings through its skirt, and parti- 130

5 tions across the interior of the cover respectively above and below said openings, both partitions having large apertures through their centers; of a trapping element remov- ably mounted in said large apertures and having inlet openings communicating with the passage between the partitions and a bead on its bottom projecting under the lower partition, and a spring carried by said

partition and having a long arm bearing up-¹⁰ ward against the bottom of the trap, for the purpose set forth.

In testimony whereof I affix my signature in presence of two witnesses.

FRED LANGBEIN.
